UNITED STATES PATENT OFFICE.

HOWARD C. SEAMAN, OF NEW YORK, N. Y.

DESIGN FOR A STOCKING.

Application filed May 18, 1927. Serial No. 22,043. Term of patent 3½ years.

To all whom it may concern:

Be it known that I, HOWARD C. SEAMAN, a citizen of the United States, residing at New York, in the county of New York and State of New York, have invented a new, original, and ornamental Design for a Stocking, of which the following is a specification, reference being had to the accompanying drawing, forming part thereof.

I claim:

The ornamental design for a stocking as shown.

HOWARD C. SEAMAN.
